UNITED STATES PATENT OFFICE.

RICHARD JOHNSON, OF LAKE BENTON, MINNESOTA.

DRAFT APPLIANCE.

1,234,036.

Specification of Letters Patent. Patented July 17, 1917.

Application filed December 22, 1916. Serial No. 138,440.

To all whom it may concern:

Be it known that I, RICHARD JOHNSON, a citizen of the United States, residing at Lake Benton, in the county of Lincoln and State of Minnesota, have invented new and useful Improvements in Draft Appliances, of which the following is a specification.

This invention relates to draft appliances adapted to be used upon buggies and light wagons and it consists in the novel features hereinafter described and claimed.

An object of the invention is to provide an appliance of simple and durable structure which is adapted to hold the swingle-trees away from the legs of the animals in the event that the traces become slack when the vehicle is passing down a hill or incline.

With this object in view the device includes a double tree made up of sections which are pivotally connected together and which are pivotally connected with the tongue, there being a spring connected with the sections and adapted to hold them in normal position. Swingle-trees are mounted upon the sections of the double-tree, and draft animals are connected with the swingle-trees in a usual manner.

In the accompanying drawings:—

Figure 1 is a top plan view of the draft appliance.

Fig. 2 is a front edge elevation of the same showing the tongue in section.

Fig. 3 is a detailed sectional view of the draft appliance cut on the line 3—3 of Fig. 1.

Fig. 4 is a similar view cut on the line 4—4 of Fig. 1.

The draft appliance comprises a bolt 1 which passes vertically through the tongue 2 in the usual manner. A clip 3 is connected at one end with the tongue 2 and at its other end receives the upper portion of the bolt 1. A plate 4 is mounted upon the upper portion of the tongue 2 and the bolt 1 passes transversely through the same. The said plate is secured in position by means of bolts 5 some of which pass transversely through the tongue 2 and also through a plate 6 positioned against the under surface of the said tongue. Other of the said bolts 5 lie at the opposite sides of the tongue 2 as shown in Fig. 4.

The double-tree of the draft appliance consists of sections 7 which are secured at their inner ends in sleeves 8. The said sleeves being pivotally mounted upon the bolt 1 as best shown in Fig. 3 of the drawing, and swingle-trees 9 are pivotally mounted at the outer ends of the sections 7 of the double-tree in the usual manner. Rearwardly disposed arms 10 are secured to the rear edges of the sections 7 in the vicinity of the inner ends thereof and are located at the opposite sides of the tongue 2. A spring 11 is connected at its ends with the rear ends of the arms 10 and is disposed transversely across the tongue 2 behind the clip 3.

The sleeves 8 are provided at their inner forward portions with shoulders 12 adapted to abut against each other when the sections 7 are in alinement with each other as shown in Fig. 1 thereby limiting the relative forward swinging movement of the sections when subjected to strain. The sleeves 8 are provided at their under sides with lugs 13 which are received in openings 14 provided in the plate 4 and which are adapted to encounter the walls of the openings 14, when the sections 7 are relieved of strain, and thus limit the rearward swinging movement of the sections 7 under the influence of the spring 11.

It will be seen that when the draft animals are hitched to the swingle-trees and exert strain upon the draft appliance the spring 11 will be elongated whereby the sections 7 of the double-trees are swung upon the pivotal connection with the tongue. In the event that the vehicle to which the draft appliance is attached begins to descend an incline and the draft strain is removed from the swingle-trees 9 the tension of the spring 11 comes into play whereby the outer ends of the sections 7 are drawn rearwardly and thus the swingle-trees and the ends of the sections 7 of the double-trees are moved back away from the hind legs of the animals. Thus in the event that the traces become slack and the draft appliance moves away from the animal and does not run up in contact with the same as is usual with the ordinary arrangement of swingle and double-trees in a draft appliance.

Having described the invention what is claimed:—

A draft appliance comprising a tongue, a bolt mounted on the same, sleeves pivotally mounted upon the bolt, tree sections attached to the sleeves, arms attached to the tree sections and located at the opposite sides of the tongue a spring connected with

the arms and disposed transversely across the tongue, a plate mounted on the tongue 10 and having openings, and lugs carried by the sleeves and having contact with the walls of the openings in the plate.

In testimony whereof I affix my signature.

RICHARD JOHNSON.
